(57) **CLAIM**

The ornamental design for a brush handle, substantially as shown and described.

DESCRIPTION

FIG. 1 is a top perspective view of a brush handle showing our new design;

FIG. 2 is a front elevation view thereof, it being understood that the rear elevation view not shown is a mirror image thereof;

FIG. 3 is a right side elevation view thereof, it being understood that the left side elevation view not shown is a mirror image thereof;

FIG. 4 is a top plan view thereof; and,

FIG. 5 is a bottom plan view thereof.

Broken lines of FIGS. 1-5 illustrate portions of the brush that form no part of the claimed invention.
